ATTORNEY

James F. Stein
WITNESS:

UNITED STATES PATENT OFFICE.

ROBERT HOSKING, JR., OF BERKLEY, VIRGINIA.

CAN OPENER.

Application filed June 28, 1926. Serial No. 119,175.

This invention relates to a can opener and seal, the general object of the invention being to provide a device having a pair of projections thereon which are adapted to be forced through a can top to make a pair of holes therein so that milk can be poured from the can and air can enter the can to replace the milk, the device being adapted to remain on the can top to close the holes to prevent dirt and insects from entering the can and also to prevent clogging of the openings by the milk.

Another object of the invention is to so form the device that a number of them can be stacked together for storage or shipment.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a top plan view of the device.

Figure 2 is an edge view with parts in section.

Figure 3 is a bottom plan view.

As shown in these views, the device is formed of a disk 1 of metal of a size to rest on the top of a can. A pair of elongated openings 2 is formed in the device adjacent the periphery thereof, the openings being oppositely arranged and a pair of tongues or projections 4 are punched from the metal, the metal between the cuts being bent downwardly to form the projections. These projections are formed with pointed ends 5 and they are oppositely arranged.

When a number of the devices are stacked together, the projections on one device will engage the openings 2 in another device and thus enable a plurality of devices to be placed together.

The device is placed on the top of a can and then the device is pressed upon to force the projections through the top of the can. Thus a pair of oppositely arranged holes will be formed in the can top, through one of which the contents of the can can be poured, the other acting as an opening for the admission of air to replace the milk. When the can is not being used, the device is left thereon so that the projections will seal the holes, thus preventing foreign matter from entering the can through the holes and also prevent the milk from clogging the holes.

Advertising matter may be placed on the top of the device, as shown in Figure 1.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A can opener and seal comprising a disk adapted to be placed over the top of a can and having a pair of projections punched therefrom, said projections being oppositely arranged on the disk, said disk also having a pair of elongated holes therein of arc shape for receiving the projections on another disk when the disks are stacked, said holes being oppositely arranged on the disk and located a quarter turn from the projections.

In testimony whereof I affix my signature.

ROBERT HOSKING, JR.
